UNITED STATES PATENT OFFICE.

REUBEN RUBENS, OF LIVERPOOL, ENGLAND.

SAFETY-RAZOR.

1,021,003.

Specification of Letters Patent. Patented Mar. 26, 1912.

Application filed April 25, 1910. Serial No. 557,523.

To all whom it may concern:

Be it known that I, REUBEN RUBENS, a subject of the King of England, residing at 14 St. John's Lane, Liverpool, in the county 5 of Lancaster, England, have invented certain new and useful Improvements in or Connected with Safety-Razors, of which the following is a specification.

This invention relates to "safety" razors 10 of that type in which a flat blade provided with a plurality of cutting edges is held between guard and cover plates.

My invention has for its object a construction whereby the razor blade may be readily 15 detached and replaced, without the necessity of detaching and replacing any of the component parts of the razor.

According to my invention, the blade cover plate which is spring controlled, is so 20 shaped in relation to an aperture in the blade, that said blade is locked between the cover and guard plates, and unlocked by the partial rotation of said cover plate.

In the annexed drawing is illustrated, by 25 way of example, one mode of embodying this invention.

Figure 1 is a plan view, Fig. 2 a part 30 sectional elevation, and Fig. 3 shows a detached blade.

Referring to the drawing, *a* represents a 35 blade which is flat, and substantially in the form of an equilateral triangle, *a'* being the cutting edges thereof, and *b* is a triangular aperture in said blade *a*.

c is a triangular guard plate provided 40 with a triangular projection *d* slightly smaller than the aperture *b* of blade *a*, so as to receive the blade and prevent its displacement when on the guard plate *c*.

e is a triangular blade holding plate secured to a spindle *f*, around which is disposed a spring *g* fitted between a collar *h* secured to said spindle and a shoulder *i* provided in the hollow handle *j*, which handle 45 is secured to the perforated guard plate *c*.

k is a button at the lower end of spindle *f*.

As shown in Fig. 1, blade *a* is locked on to the guard plate *c* by plate *e*, under the influence of spring *g*.

When it is required to remove a blade *a* for stropping, or renewal, spindle *f* is first

pressed upward—against the resistance of spring *g*—by means of a button *k*, and then turned until plate *e* coincides with the projection *d* of guard plate *c*, when the blade 55 *a* may be removed and another blade fitted; spindle *f* is then pressed upward and turned again to the position shown in Fig. 1 and released, when holding plate *e* firmly holds the new blade *a* in position on the guard 60 plate *c*.

Having now described my invention what I claim as new and desire to secure by Letters Patent is:—

1. In safety razors of the type herein described, in combination a guard plate, a cover plate rotatable relatively thereto, a razor-blade between these two plates and with an aperture, said cover plate and said blade-aperture being of such sizes to cause 70 said blade to be locked or unlocked on the partial rotation of said cover plate to bring said aperture and cover plate into or out of register with each other; a hollow handle attached to the guard plate and provided with 75 an internal shoulder; a spindle rigidly attached to the cover plate; a collar on said spindle, and a spring disposed around said spindle between said shoulder and said collar. 80

2. In safety razors of the type herein described, in combination a guard plate, a cover plate, a razor-blade provided with an aperture, said cover plate and said aperture being of such shape that said blade is locked or unlocked on the partial rotation of said cover plate to bring said aperture and cover plate into or out of register with each other; a hollow handle attached to the guard plate and provided with an internal shoulder; a spindle secured to the cover plate; a collar on said spindle; a spring disposed around said spindle between said shoulder and said collar, and means for rotating said spindle and cover plate relatively to the guard 90 plate. 95

In testimony whereof I affix my signature in presence of two witnesses.

REUBEN RUBENS.
